(57) **CLAIM**

The ornamental design for a regulator bracket, as shown and described.

DESCRIPTION

FIG. 1 is a perspective view of a regulator bracket showing our new design;

FIG. 2 is a front view thereof;

FIG. 3 is a rear view thereof;

FIG. 4 is a left side view of the regulator bracket, a right side view being identical thereto;

FIG. 5 is a top view of the regulator bracket, a bottom view being identical thereto; and,

FIG. 6 is a perspective view of the regulator bracket, a regulator being shown in phantom as environmental structure only and therefore forming no part of our claimed design.
